UNITED STATES PATENT OFFICE.

CHARLES ADAMS SIMPSON AND IILTYD CUNLIFFE VIDAL, OF DUNEDIN, NEW ZEALAND.

AIR PUMP.

Application filed April 9, 1923. Serial No. 630,914.

This invention relates to air pumps for use principally in connection with motors.

The object of the invention is to convert one or more of the cylinders of an internal combustion engine into an air pump, and utilize the remaining cylinders as a power unit to operate the said air producing cylinder or cylinders, for the purpose of inflating pneumatic tires, actuating pneumatic tools, 10 and to operate on a lifting jack by air pressure.

The method of employing the cylinder is part of the invention, together with the method of cutting out the cylinder (i. e. preventing flow of petrol gas into the engine cylinder on its induction stroke, and converting the exhaust stroke of the piston to obtain air pressure by preventing air escape- 15 ment through the exhaust valve) in combination with the means employed in accom- plishing the cutting out process.

In different types of engines, different means will be employed; as for example, an engine where the cylinders are supplied with fuel through one induction outlet controlled by overhead valves will have different apparatus (for the cutting out process) to the under type of valve having the same class of induction pipe. An individual outlet in 20 induction pipe with overhead valve mechanism may have different cutting out means to either of the first mentioned types. Where the valve plug has been dispensed with, a different design to any of the above varieties 25 will be employed.

The accompanying drawings illustrate a unit used in conjunction with valves of the under operated type; or the unit may be made to include the valve plug in the new- 30 manufacture if or when necessity arises; for example, if the diameter of the plug aperture is not sufficient to permit the entry of the converting unit, then it may be found necessary to increase the size of the said plug; in 35 these circumstances a new valve plug would be included, but for the purpose of this invention it is assumed that the converting unit will pass through the valve plug aper- ture, and the drawings represent such a unit, 40 in which:—

Figure 1 is a vertical cross section of part of an engine showing the cylinder, piston, combustion chamber, valve plug and converting unit.

Figure 2 is a cross sectional view of part

of a cylinder, combustion chamber and valve, showing the converting unit out of action, with a sparking plug in position for ordinary combustion engine action.

There is an air outlet fitting for a coupling 1, while 2 indicates the usual type of flex for use in forming a duct for air communication between air pumps and tires; and between air pumps and lifting jacks; the said fitting is preferably in the form of a compression cock, having a tapered plug valve 3 with operating means 3^a passing through the body part 4 of the fitting. The fitting is screw threaded at 5, of preferably standard sparking plug size. There is an intermediate part 6, which is screw threaded at 6^a to register with the thread 5 of the fitting. The said intermediate part 6 is preferably in two pieces, the lower part 6^b provides a valve hood 6^c adapted to cover the head of 75 the valve 7.

There is an apertured stem 6^d extending upwards from the valve hood 6^c fitted with a jam nut 8. The said stem 6^d is screw threaded at 6^e to register with an internal screw 80 thread in the upper part 6^f of the intermediate part 6. There is a suitable washer 9 engaging the upper surface of the jam nut 8 and the lower face of the upper part 6^f of the intermediate part 6. When the two parts 85 6^b and 6^f are screwed together through the registering of the said screw thread 6^e, there should be a sufficient distance between the face 9^a of the washer 9 and the face 10 of the valve plug 10^a so that the hood 6^c will 90 be lifted clear of the valve 7 to have a suitable range of adjustment to put the cylinder out of action as a power unit when it is required as an air unit, and yet open sufficiently to enable the cylinder to operate as 95 an internal combustion engine unit.

The valve plug 10^a is of the usual type, threaded at 10^b to register with the screw threaded part of the cylinder, and is provided with a shoulder 10^c, and washer 10^d, 100 to form a joint with the face of the said cylinder as in the manner of the well known type of valve plug.

The adjustment of the intermediate part 6 is exercised from the upper end on turning an extension 6^e; a portion of the extension 6^e may be of hexagon shape to take an ordinary spanner, or castellated to take a cotter spanner. There is a washer 11, used to form a tight joint when the unit is adjusted to cut 110

off the supply of petrol gas and convert the cylinder into an air pump.

Referring again to Figure 2, which as before stated shows the converting unit out 5 of action; when the unit is in operation to direct air pressure through the apertures 6^M, the intermediate part 6 of the unit is screwed downwards until the hood 6^C covers the valve 7 as in the manner illustrated in 10 Figure 1.

The valve hood 6^C, on adjusting the intermediate part 6, covers the valve 7; a flex 2 is adjusted to the fitting on the intermediate part 6. During the suction stroke 15 of the piston in the converted cylinder, air is admitted through suitable inlet valve 4^A, and upon the compression stroke and/or compression and exhaust strokes, the air is forced (by the medium of apertures 6^M in 20 the stem 6^D of the lower part 6^B) through the air duct in the flex 2 to inflate the tire tube or operate upon a lifting jack.

What we claim as new and desire to secure by Letters Patent is:—

25 1. In combination, an internal combustion engine cylinder having a gas passageway, a valve for controlling the movement of gas in said passageway, a hood arranged within the combustion chamber of the cylinder to cover said valve and prevent the passage of gas through the passageway, a hollow plug connected to the hood and communicating with the combustion chamber of the cylinder, a conduit connected to said plug and 30 provided with an air inlet valve and an air outlet pipe, and a piston arranged in the cylinder for drawing air into the cylinder through the air inlet valve and for forcing the same out through said plug, conduit and 35 pipe.

40 2. The combination with an internal combustion engine cylinder and piston, of a gas passageway communicating with the combustion chamber of the cylinder, a valve controlling the movement of gas through said passageway, a hood in the combustion chamber arranged to obstruct said passageway and prevent the passage of gas through the latter even though said valve is open, means 45 to permit axial movement of said hood, a hollow plug connected to the hood and communicating with the combustion chamber, a conduit connected to the plug and provided with an air inlet valve, and a pipe connected 50 to said conduit for discharging air from the cylinder.

55 3. An air pump attachment for an internal combustion engine having a valve including a hollow plug provided with means 60 for attaching the same to an engine cylinder, a hood arranged at one end of said plug and adapted to enclose the face of said valve, said plug being provided with slots to permit its interior to communicate with the 65 combustion chamber of a cylinder, said plug

being provided at one end with a threaded aperture of a size to receive an ordinary spark plug, a second plug having a screw-threaded extension adapted to engage the threads of said aperture, a conduit connected 70 to the second plug and provided with an air inlet valve, and a pipe connected to the conduit for discharging air from the latter.

4. In combination, an internal combustion engine cylinder having a gas passageway 75 controlled by an axially movable valve, a piston in the cylinder, an axially movable hollow plug, coaxial with the axis of the valve and having its interior communicating with the combustion chamber of the cylinder, a hood at one end of said plug arranged to enclose the inner face of the valve head and to obstruct the gas passageway, said plug being provided with a threaded aperture of a size suitable to receive an ordinary spark plug, a conduit having a threaded extension projecting into said aperture and engaging the threads of the latter, an air inlet 80 valve for the conduit, and a pipe connected to the conduit and arranged to discharge air 85 from the latter.

5. In combination, an internal combustion engine cylinder provided with a gas passageway having a control valve, an adjustable hollow fitting extending into the combustion chamber of the cylinder for cutting off the gas passageway from the combustion chamber and covering said valve, and a valved conduit connected to said fitting to convert the internal combustion engine cylinder into an air pump.

6. An air pump device for use with internal combustion engines including a ring provided with internal and external screw-threads and with upper and lower shoulders, 105 a hollow plug provided with internal and external threads, the latter being adapted to engage the internal threads of the ring, an outwardly extending flange at the upper end of the plug extending over said upper shoulder, a packing ring between the last mentioned shoulder and flange, a second packing ring arranged intermediate the ends of said plug and being adapted to engage the lower shoulder of the threaded ring, said plug being axially movable in the threaded ring, a hood arranged at the lower end of the plug to cover the valve of an internal combustion engine, said plug being provided with slots 110 to permit its interior to communicate with the combustion chamber of an engine, a conduit having a threaded extension engaging the internal threads of the plug, an air inlet valve for said conduit, and a discharge pipe 115 connected to the conduit.

In testimony whereof, we affix our signatures.
